UNITED STATES PATENT OFFICE.

JOSEPH KENNEDY, OF RICHMOND HILL, NEW YORK, ASSIGNOR TO THE CLEMENTS CO.,
OF NEW YORK, N. Y., A CORPORATION OF NEW YORK.

EXPANSION-SHIELD.

1,304,887.

Specification of Letters Patent.

Patented May 27, 1919.

Application filed August 20, 1917. Serial No. 187,063.

To all whom it may concern:

Be it known that I, JOSEPH KENNEDY, a citizen of the United States of America, and a resident of Richmond Hill, county of 5 Queens, and State of New York, have invented certain new and useful Improvements in Expansion-Shields, of which the following is a specification, reference being had to the accompanying drawings, forming a part thereof.

My invention relates to bolt anchors and has special reference to such as are constructed of sheet or other deformable metal.

One object of my invention is to provide 15 a simple device of the aforesaid character which may be manufactured in large quantities at small cost, and which shall be especially rigid as compared with devices of the prior art constructed of sheet metal or 20 the like of substantially uniform thickness.

Another object is to provide a tapered expansion shield of metal of uniform thickness but to provide excess metal at the part thereof of reduced external diameter, by 25 having rigid ribs or flanges, or ribs or flanges which are adapted to be folded or crushed by the expansion of the shield between the shield and the wall of the hole in which it is inserted, which ribs or flanges 30 in either case provide the excess metal necessary for a good anchorage.

Another object of the invention is to crimp or fold the metal of the shield inwardly along substantially longitudinal lines in such a manner that the insertion of 35 a bolt will force these crimped or folded parts outwardly so that the metal of the shield will entirely or substantially surround the threads of the bolt and to provide by 40 flanges or folded ribs, excess of metal at such crimped parts of the shield.

In order that my invention may be thoroughly understood, I will now proceed to describe the same in the following specification, and then point out the novel features 45 thereof in appended claims.

This application is a continuation in part of two copending applications for patents Serial Nos. 19,523 and 20,619, filed by me respectively on the 6th and 12th days of April, 50 1915.

Referring to the drawings:

Figure 1 is a longitudinal sectional elevation of a bolt anchor made in accordance with and embodying my invention, shown 55 in its expanded condition as utilized in holding a bolt or screw in a wall of concrete or other material. The section in this figure is taken on the irregular line 1-1 of Fig. 2.

Fig. 2 is a transverse sectional elevation 60 on an enlarged scale, of the parts shown in Fig. 1.

Fig. 3 is a plan view of a blank or stamping from which the shield shown in Figs. 1, 2-6, is formed.

Fig. 4 is a plan view, and

Fig. 5 is a side elevation of the shield shown in Figs. 1 and 2 before expansion.

Fig. 6 is an end elevation of the same form of shield.

Figs. 7, 8 and 9 are end views of modified forms of shields which also embody this invention.

Fig. 10 is an end view of a shield of still further modified construction in which a 75 greater excess of metal is provided at the inner end of the shield.

Fig. 11 is an end view of a shield which also embodies this invention, in which the excess metal is provided by portions which 80 are folded back upon the walls of the shield before the shield is expanded.

Fig. 12 is a sectional end elevation of a form of shield in which the folded portions which provide the required excess of metal 85 are at other than the lines of division between the expansion members of the shield.

Fig. 13 is an end elevation of a form of my invention in which the shield is a circumferentially continuous tube.

Fig. 14 is an end elevation of a shield embodying this invention which is constructed from a blank bent transversely into a tube.

Like characters of reference designate 90 corresponding parts in all the figures.

15 designates a wall of concrete, brick or the like in which is formed a substantially cylindrical hole or opening 16 to which wall a body 17 is to be secured by a lag bolt 18 which extends through a suitable hole in the 100 body 17.

20 is an expansion shield or anchor into

which the bolt is screwed. This may be constructed of sheet metal by first cutting out a blank like that shown in Fig. 3. As here shown this comprises a central body 21, 5 and in this case two flaring side members 22 and 23 which project from the body 21. The blank is then formed in a die which makes the body 21 into a thimble and the side members into a tubular extension of the 10 thimble. The end of the thimble is then cut off to provide a clearance hole for the bolt at the outer end of the shield and transforms the thimble into a substantially cylindrical ring or yoke 24. Before this is done 15 the edges of the side members are bent upwardly along some such lines as those indicated at 25 in Fig. 3 to form the outwardly curved tapered flanges or ribs 26. The metal between the lines 25 is also corrugated on spiral lines to form in the finished shield, screw threads with which the threads of the bolt may engage. These corrugations as seen from the outside of the shield are 20 designated 27. 25 At or near the lines where the ribs or flanges 26 bend outwardly from the shield, the latter is bent inwardly or indented as at 28 along lines which taper to the same extent with, but in the opposite direction to, 30 the taper of the ribs or flanges. This results in the tube being cylindrical at the outer end and having its bore tapered toward the inner end of the shield to a cross-section somewhat similar in form to that of 35 an hour-glass, as seen in Fig. 6. It also results in the outer ends of the ribs or flanges lying in an imaginary cylinder of the diameter of the ring or yoke 24. 40 Before specifically describing the devices shown in the other figures of the drawing, I will describe the operation of this form of my invention. 45 The shield is inserted in the hole 16 which is drilled of a diameter to allow the ring 24 to fit. The ribs or flanges 26 then serve to centralize the shield in the hole. When a bolt is screwed into this shield it will force the indentations 28 outwardly causing the inner part of the shield to assume a cylindrical form which surrounds the threads of 50 the bolt. The ribs or flanges 26 will during this operation be folded down onto the outside of the shield and forced into the wall of the hole as shown in Fig. 2, and in the lower 55 part of Fig. 1. These ribs or flanges provide an excess of metal which increases toward the inner end of the shield and thus the device forms a secure anchorage for the bolt. 60 The indentations 28 which contract the inner end of the shield are shown as causing this contraction to give the inner end of the shield an hour-glass form of cross-section in Figs. 6-12, which is the case whenever there 65 are two of these indentations diametrically

disposed. But where there are more than two of these indentations as at 28^A, in Fig. 13, or 28^B in Fig. 14, the form of cross-section of the inner end of the shield is quite different but this does not materially change the operation or the function of the device. 70

In Fig. 7, the ribs or flanges 26^A are similar to those shown in Fig. 6 but are not spread apart as in the latter figure. 75

The ribs or flanges 26^B in Fig. 8 are bowed apart so that during expansion they are crushed together. But their function of centering the device before expansion and of providing excess metal for anchorage purposes, remains the same. 80

Where a greater amount of excess metal is desired the constructions shown in Figs. 9 or 10, may be used. In Fig. 9 the outwardly projecting tapered ribs 26^C have their 85 outer edges 29 bent around into the periphery of the imaginary cylinder projecting from the ring 24. In the construction illustrated in Fig. 10, the ribs or flanges 30 not only diverge as in the form shown at 26 in 90 Fig. 6, but are doubled back as at 31 and out again as at 32 to form a greater amount of excess metal.

The form shown in Fig. 11 is added to show that the invention is not limited to ribs 95 or flanges which are folded by the expansion caused by the insertion of a bolt. In this case the ribs or flanges 33 are folded down onto the outer surface of the shield during its manufacture. They may be tapered as in the other cases to correspond with the taper of the indentations 28. 100

It is not necessary of course that the tapered indentations 28 are at the lines of separation between the arms 22 and 23 of 105 the blank. Fig. 12 shows the tapered indentations 28 midway between the lines of separation, and the ribs 34 formed by folding the metal together at or near these lines of indentation. 110

Fig. 13 as I have stated, shows a device constructed of a circumferentially continuous tube which before the folded tapered ribs 35 and indentations 28^A were made therein would be in the form of a truncated 115 cone on account of the excess metal at its inner end.

It is not necessary that the shields be constructed in accord with the method which has been described. They may be made 120 also by bending a blank transversely to form a shield which embodies this invention such as that shown in Fig. 14. In this case there are four tapered indentations 28^B opposite three of which are folded ribs 36 and 125 opposite the other are a pair of flanges 37 which perform the same function.

Neither is it essential that the bore and ribs be tapered. When a tapered bore is desired it is not necessary that it be formed 130

during the manufacture of the device. If the bore is cylindrical in the finished device the ribs or flanges will cause the bending inwardly or indenting of the shield to take 5 place when the shield is driven into the hole which is to receive it. Tapering the ribs downwardly toward the inner end of the shield will facilitate this operation. After the shield is driven into a hole a bolt is 10 inserted which, expanding the shield into tight engagement with the walls of the hole and forms a secure anchorage.

While the bolt anchors of my invention may be readily formed from commercial 15 sheet metal, such as sheet iron, steel or brass, having a substantially uniform thickness, I have used the term "sheet metal" herein in a broader sense and intend to include not only what is known as sheet 20 metal but also rolled metal such as lead, or cast or wrought metal, and malleable iron which is adapted to be shaped to produce the desired form.

Various other modifications than those 25 which I have shown and described may be effected within the spirit and scope of my invention, and I intend that only such limitations be imposed as are indicated in the appended claims.

30 What I claim is:

1. A bolt anchor comprising a substantially circumferentially continuous tubular body adapted to receive the threads of a bolt, a tapered depression therein reducing 35 the bore of the tube toward the inner end thereof, and an oppositely tapered rib to provide excess metal at the inner end of said body.

2. A bolt anchor comprising a substantially circumferentially continuous tubular body adapted to receive the threads of a bolt, a plurality of tapered depressions therein reducing the bore of the tube toward the inner end thereof, and a plurality 45 of oppositely tapered ribs to provide excess metal at the inner end of said body.

3. A bolt anchor comprising a substantially circumferentially continuous tubular body forming two expansion members divided from each other through at least a part of the length of the anchor, and adapted to receive the threads of a bolt, the adjacent edges of said members being bent outwardly and constructed to form longitudinal 55 ribs tapered to increase in height toward the inner end of the anchor, and members having oppositely tapered depressions therein adjacent said ribs.

4. A bolt anchor comprising a substantially circumferentially continuous tubular body adapted to receive the threads of a bolt, a pair of tapered depressions therein forming a bore varying in cross-section from a circle to an hour-glass form from end to 65 end, and oppositely tapered ribs adjacent

said depressions to provide excess metal at the inner end of said body.

5. A bolt anchor comprising a substantially circumferentially continuous tubular body forming two expansion members divided 70 from each other through at least a part of the length of the anchor and adapted to receive the threads of a bolt, each of said members having ribs extending outwardly adjacent the plane of division between said members, and inwardly extending tapered depressions adjacent to said ribs, forming a bore varying in cross-section from a circle to an hour-glass form from end to end.

6. A bolt anchor comprising a substantially circumferentially continuous tubular body adapted to receive the threads of a bolt, a tapered depression therein reducing the bore of the tube toward the inner end thereof, and an oppositely tapered rib to 80 provide excess metal at the inner end of said body, said tube being arranged when expanded to surround the threads of a bolt.

7. A bolt anchor comprising a substantially circumferentially continuous tubular 90 body adapted to receive the threads of a bolt, a plurality of tapered depressions therein reducing the bore of the tube toward the inner end thereof, and a plurality of oppositely tapered ribs to provide excess 95 metal at the inner end of said body, said tube being arranged when expanded to surround the threads of a bolt.

8. A bolt anchor comprising a substantially circumferentially continuous tubular body of deformable metal adapted to receive the threads of a bolt, said body having a depression therein reducing the bore of the tube, the metal of said tube being folded near the line of said depression to provide 100 an excess of metal at said part of the tube.

9. A bolt anchor comprising a substantially circumferentially continuous tubular body of deformable metal adapted to receive the threads of a bolt, said body being arranged to be bent inwardly to reduce its bore before a bolt is inserted therein, the metal of said tube being folded near said 110 inwardly bent part of the tube to provide an excess of metal at said part of the tube.

10. A bolt anchor comprising a substantially circumferentially continuous tubular body of deformable metal adapted to receive the threads of a bolt, said body being arranged to be bent inwardly along longitudinal lines to reduce its bore before a bolt is inserted therein, the metal of said tube being folded near said lines to provide excess metal at said parts of the tube, said tube being arranged when expanded to surround 120 the shank of a bolt.

11. A bolt anchor comprising a substantially circumferentially continuous tubular body of deformable metal arranged to be bent inwardly along longitudinal lines to 130

reduce its bore and to have a substantially cylindrical outer surface before a bolt is inserted therein, the metal of said tube being folded near said lines to provide excess metal at said parts of the tube, the inner surfaces of said tubular body being provided with substantially continuous corrugations adapted to receive the threads of a bolt, said tube being arranged when ex-

panded to surround a bolt and to substantially circumferentially engage the threads thereof. 10

In witness whereof I have hereunto set my hand this 17th day of August, 1917.

JOSEPH KENNEDY.
